UNITED STATES PATENT OFFICE.

ANSON HILGER, OF PIERRE, DAKOTA TERRITORY.

FAN ATTACHMENT FOR SEWING-MACHINES.

SPECIFICATION forming part of Letters Patent No. 269,669, dated December 26, 1882.

Application filed July 26, 1882. (No model.)

To all whom it may concern:

Be it known that I, ANSON HILGER, a citizen of the United States, residing at Pierre, in the county of Hughes and Territory of Dakota, have invented certain new and useful Improvements in Fan Attachments for Sewing-Machines, &c.; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a fan attachment for sewing-machines, tables, desks, and similar articles of furniture; and it consists in the construction and arrangement of devices for producing a current of air and in the manner of attaching and operating said mechanism, as will be hereinafter more fully described and claimed.

In the annexed drawings, which illustrate my invention, Figure 1 is a side view of the fan and operating mechanism, showing the manner of connecting the supporting-standard to the table of a sewing-machine. Fig. 2 is a view of the same, taken at a right angle to Fig. 1. Fig. 3 is a perspective view of the fan and connected spindle. Fig. 4 illustrates the manner in which the wheel or pulley over which the driving-belt is passed may be connected with or applied to a wheel on any machine desired. Fig. 5 represents an arrangement of gearing for reversing the motion of the fan.

Like letters are used to designate the same parts in the several views.

The fan-wheel A is made of any suitable material, and is provided with fans or blades a, that may be formed by cutting the body of the fan radially and bending the blades to one side at any desired angle, as shown in Figs. 2 and 3; or the fan-wheel may consist of a continuous disk having the blades or fans secured to one side in any convenient manner. This fan-wheel is provided with a shaft, B, to one end of which it is secured by any suitable means, so as to be detached therefrom when desired. The shaft B carries near its other end a pulley or grooved spindle, b, and is journaled in suitable bearings formed in the arms c c, which are secured to the upper end of a standard, C, that

is adapted to be attached in any desired position. This standard has a foot or base, c', and may be conveniently secured to the table or bed of a machine, or in any suitable place, by means of a clamp, D, having a set-screw, d, so that the part may be readily detached when desired. In attaching this device to a sewing-machine, table, work-bench, or other place where the cooling effects produced by the revolution of the fan are desired, and where there is a convenient motive power—such as a revolving wheel, E—it will be seen that the foot of the standard C will be clamped to the table or support F in convenient proximity to said wheel, from which a band, belt, or cord, e, is passed to the pulley b, that is journaled between the arms c c of the standard. The power imparted to the wheel E is thus transmitted to the pulley b, so as to cause the fan-wheel A to revolve with the shaft B, and thereby create a cooling current that will contribute greatly to the comfort of a person working at the machine or table to which the device is attached.

When the device is to be attached to a machine that is not provided with a convenient wheel or pulley for the attachment of the cord e, I have found it useful to employ a wheel or pulley, G, having arms g, provided with spring-clamps g', that may be made to clasp the inner edge of the rim of a spoke-wheel, H, as shown in Fig. 4, the pulley G being thus caused to rotate with the wheel H, and thereby actuate the fan-wheel through the cord or belt connecting the pulley G with the pulley on the fan-shaft.

If desired, the fan-wheel may be arranged to rotate in a direction opposite to that in which the motive power is applied. This result may be effected by any convenient means—such as that illustrated in Fig. 5, in which the pulley b is secured to a short tubular shaft, B', that is journaled in the bearings c c, and carries on its end nearest the fan-wheel a bevel-gear, f. The shaft B, to which the fan-wheel A is secured, will then be provided with a bevel-gear, g, and be of such diameter or reduced at one end as will permit its being passed into the tubular shaft B'. An arm, h, projecting from the standard C beneath the gears f and g, is provided with a stud, i, upon the upper end of which is journaled a bevel-gear, k, which is arranged in a horizontal position beneath the gears f and g, so as to mesh therewith and thereby enable

the shaft B and attached fan to be rotated in a direction opposite to that in which the shaft B' is revolved. The stud *i* is passed through an opening in the arm *h*, where it is held by a 5 set-screw, *m*. This set-screw may be removed, so as to allow the gear *k* to be lowered, and thus become disengaged from the gears *f* and *g*, when the set-screws *s*, attached to the tubular shaft B', may be tightened, so as to clutch 10 the shafts B and B' and allow them both to be rotated in the same direction, as if one shaft only was used.

Having thus described my invention, what I 15 claim as new, and desire to secure by Letters Patent, is—

The combination of the standard C, having arms or bearings *c c* and arm *h*, the tubular shaft B', journaled in the bearings *c c* and having pulley *b*, bevel-gear *f*, and set-screws *s s*, the shaft B, adapted to enter the tubular shaft 20 and provided with fan-wheel A and bevel-gear *g*, and the adjustable stud *i*, having bevel-gear *k*, all substantially as and for the purpose described.

In testimony whereof I affix my signature in 25 presence of two witnesses.

ANSON HILGER.
